(57) **CLAIM**

The ornamental design for an octagon bottle, as shown and described.

DESCRIPTION

FIG. 1 is a top, front, right side perspective view of a bottle showing my new design;

FIG. 2 is a front elevational view thereof;

FIG. 3 is a rear elevational view thereof;

FIG. 4 is a front, right corner elevational view thereof;

FIG. 5 is a rear, left corner elevational view thereof;

FIG. 6 is a top plan view thereof;

FIG. 7 is a bottom plan view thereof; and,

FIG. 8 is an enlarged detail of the FIG. 8 detail area shown in FIG. 1.

The dash-dash-dash type broken lines shown on the bottom surface in FIG. 7 are included for the purpose of illustrating environmental structure and form no part of the claimed design.

The dot-dash-dot-dash type broken line shown in FIGS. 1 & 8 defines the area of the enlarged detail shown in the FIG. 8 drawing view.
